Primary Examiner — Andrew Kerr

Assistant Examiner — Courtney Clark-Rasheed

(57) CLAIM

The ornamental design for a combined drinking lid with handle, as shown and described.

DESCRIPTION

FIG. 1 is a bottom and rear perspective view of a combined drinking lid with handle design showing my new design;

FIG. 2 is a top and front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detailed view of encircled area 9 in FIG. 8.

The broken lines in the drawings depict portions of the combined drinking lid with handle that form no part of the claimed design.

1 Claim, 9 Drawing Sheets
